METHOD OF MAKING TOY FURNITURE
AND THE LIKE

Philip E. Gier, Conrad, Iowa

Application February 8, 1932, Serial No. 591,569

1 Claim. (Cl. 144—309)

The object of this invention is to provide an improvement in the art of making and producing a considerable number of similar objects from wood or other material with the particular purpose of conserving material and reducing labor costs.

A further object is to provide an improved method for forming a plurality of objects which are alike or alike in some important features, said method including the steps of producing a molded or formed strip of material having a cross sectional contour conforming to the contour of the objects to be made and then severing the molded strip transversely into suitable blocks corresponding to one of the dimensions of the object and then further treating such block in suitable manner to produce the finished articles.

A further object of the invention is to provide an improved method of producing toy furniture, toy animals and the like, or other objects from material such as wood, which improvement includes the steps of forming a strip of the material to a certain cross sectional contour, then cutting the strip transversely into suitable lengths or blocks, and finally applying the necessary finishing touches to produce the desired object.

My invention also contemplates in some instances the additional steps of operating on the cut-off blocks of molded strip by cutting each block to form the blank for two similar objects in reversed position, and then removing the excess portions of the material before the finishing touches are applied.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:—

Figure 1 is a perspective view of a portion of a molded strip of material from which a plurality of objects may be formed, such for instance as chairs of a toy furniture set.

Figure 2 is a side elevation of a block or section cut from the strip shown in Figure 1, and illustrating how such block or section may be severed on an irregular line to produce two of the objects, these objects occupying relatively reversed positions in the block.

Figure 3 is an end view of one of the blanks cut from the block shown in Figure 2 preparatory to the step of removing excess material to form the legs of the chair and produce the finished object.

Figure 4 is a perspective view of a toy chair

formed according to my method from the molded strip, block and blank illustrated in Figures 1, 2 and 3.

Figure 5 is a perspective view of a differently molded strip for forming a different type of chair.

Figure 6 is a side elevation of a length or block cut from the strip shown in Figure 5 and illustrating how this block may be severed on an irregular line for forming the blanks for two of the desired objects.

Figure 7 is a plan view of a chair constructed according to this method from the molded strip of Figure 5 and block of Figure 6, illustrating how certain excess material is removed from the blank to finish forming the seat and back of the chair.

Figure 8 is a perspective view of the completed object so formed.

Figure 9 is a side elevation of a portion of a molded strip from which a block may be cut as indicated by the broken line for forming the blank for a toy clock.

Figure 10 is a front elevation of a toy clock which may be produced from the strip shown in Figure 9.

Figure 11 is a side elevation of a toy animal, some of the different members of which may be formed according to my method.

Figure 12 is a perspective view of a molded strip from which blocks or sections may be cut as indicated to produce one of the members, namely the rear leg member of the toy shown in Figure 11.

Figure 13 is a perspective view illustrating steps in the method of forming a molded strip, severing them into sections and then cutting each section to produce two articles which are alike in some respects, but dissimilar in other respects.

Figure 14 is a side elevation of a molded strip which may be cut on transverse lines to form blocks or sections, each of which may be cut on an irregular line to produce two similar ornamental objects such as book ends.

Figure 15 is a perspective view showing one of the book ends produced by following the method illustrated in Figure 14.

Figure 16 is a cross section of a molded strip which may be employed for making ornamental objects such as candlesticks.

Figure 17 is a side elevation of the strip shown in Figure 16 illustrating how the strip may be cut on various lines to produce the finished articles.

Figure 18 is a perspective view of a candlestick.

which may be produced by following the method illustrated in Figures 16 and 17.

The material ordinarily employed for making toy objects, ornamental articles and designs or the like in accordance with my invention is wood, although it is thought that under some circumstances other suitable material may be employed.

The first step is to take a strip of material of any desired length and of suitable transverse dimensions and to shape said strip to the desired cross sectional area or contour. This contour is determined by the contour of the object which it is desired to form from the strip. In this connection it may be said that the contour of the strip of material may in some instances conform to and be determined by the desired contour of the finished object in plan view, and in other instances will conform to and be determined by the shape of the object in side elevation.

This first step of shaping the strip to the desired contour may be referred to as molding the material. It may be accomplished by running a strip of material through a wood working machine known as a molder or sticker, which is a machine having suitable knives for cutting and shaping the four sides of the strip at one operation. This is the most economical method of forming or molding the strip so far as time and labor are concerned, although the operation may be carried out by using an ordinary shaper or planer having cutters for operating on one side of the strip at a time.

It will be readily understood that in some instances all four sides of the strip will be alike when molded, and that in other instances two opposite sides will be alike and will be different from the other two sides, which may be alike or different, and that in some instances all of the lateral sides of the strip will be different from each other. This is in all instances determined by the contour of the object or series of objects to be produced and it will be further understood that in many instances all of the finished objects produced from a given strip will be similar to each other. In other instances the objects produced from a given strip will be similar to each other throughout portions of their contours, but dissimilar in other portions so that the objects will be alike in some important features but not in all. This similarity of distinctive details of contour is of the essence of my invention, which contemplates an economical method of forming a considerable number of such objects.

In Figures 1, 2 and 3 there are shown different steps in the method of forming a toy chair which is shown in Figure 4.

In Figure 1 the molded strip of material is designated generally by the character A. This particular strip embodies a substantially circular body portion 10 having four longitudinally extending similar ribs 12 which are arcuate in section and are spaced about the body.

The molded strip A of Figure 1 is cut into suitable lengths or blocks as shown in Figure 2, and each of said blocks contains the material for the blanks B and C for two of the chairs. The block is separated into the two blanks B and C by severing along the irregular line 14 which cut may be made by using a band saw or the like. It will be noted that the blanks B and C are relatively reversed in the block and that the wide portion which is to form the base of one chair is opposite to the narrow portion which is to form the back of the other. When the block is cut

on the line 14 it produces the two blanks B and C, each having a wide part 16 which is to form the base or lower part of the chair and an upwardly projecting narrow part 18 at one side thereof which is to form the back of the chair, this being accomplished by cutting on a substantially Z-shaped line as indicated in Figure 2.

The next step of this particular embodiment of my improved process consists in removing excess material from each of the blanks B and C. This is accomplished by placing the blank in inverted position as indicated in Figure 3 and boring out the major part of the material in the base portion 16 to produce the legs of the chair. It will be understood that a small segment has already been removed by cutting on the line 14, thus leaving the straight boundary line 20 at one side of the base. The remaining portion between the ribs 12 is removed on the substantially circular line 22 by the use of a bit or boring tool to leave only the four spaced ribs 12 which thus become the legs of the chair. The material between the ribs 12 is removed to a plane suitably spaced from the upper margin of the base in order to leave the seat portion 24 of the chair which forms a connection between the four spaced legs 12 and also forms a support for the back member 18 of the finished chair as shown in Figure 4. The boring operation may be carried out by any suitable bit or boring tool, preferably of the rim guide type, such for instance as the Forstner bit. By using this particular type of bit the bottom of the cut is left substantially smooth and plane and moreover, this type of bit is capable of cutting a part of a circle more readily than the more common center guide type of bit.

The chair is then ready to receive the finishing touches such as painting and decorating.

This furnishes a good example of how my improved method may be employed for producing one type of object from a molded strip whose contour conforms substantially to the contour in plan view of the object to be produced. It will be observed that the seat 24 of the finished chair carries out substantially the outline of the molded strip A except that its front edge is formed by the straight line 20 of the blank which results from cutting on one end portion of the line 14 of Figure 2 and as before stated the portion between the ribs 12 is cut away at the base to produce the legs of the chair and that no further cutting operations are required to produce these legs after the cut on the substantially circular line 22 by using the boring tool. The upwardly projecting back member 18 is left at that side of the seat 24 opposite to the straight line cut 20 and this back member may be left in the condition resulting by cutting along the line 14 or its side margins may be finished on curved lines such as shown in Figure 4 by using any suitable cutting or abrading implement.

A slightly different embodiment of the method for producing a different type of chair is illustrated in Figures 5 to 8 inclusive. By carrying out the method as here illustrated there is produced an article of toy furniture representing a lounging chair or overstuffed chair. In Figure 5 there is illustrated the formed or molded strip D which is first produced in any suitable manner by the use of suitable tools or machinery as previously suggested. This strip is symmetrical and includes a substantially rectangular body portion 26 having at its corners arcuate ribs 28. On two of its opposed sides it is formed with

a pair of lesser arcuate ribs 30 and on each of other adaptation of this method for producing its other two faces is formed with a rather flat a toy figure to represent a pig or other animal. projection 32 having a plane face. The strip The body portion 54 of the figure toy may be 80 D. is cut into suitable lengths or sections by using a sawsaw or bandsaw or other suitable blanks or sections of appropriate thickness as cutting tool to produce blocks of suitable length previously indicated. In a similar way the front as shown in Figure 6. legs 56 of the animal may be produced from 85 Each of these blocks includes the material for another molded strip and the rear legs 58 from two chairs and the blanks for these two chairs still another strip which is shown in Figure 12 10 are separated by cutting the block on an irregular and designated generally by the character H. 85 or ogee curve line 34 to produce the two blanks The strip H is formed of any suitable length and to the desired sectional contour to represent which are designated E and F. 90 Each blank thus formed has at one side an at certain portion of the figure which is to be narrow portion 36 which becomes the back of the produced, such as the leg 58. After being formed 15 chain and also has a broad base portion 38 and or molded the strip H is cut into sections of suit- an intermediate portion of intermediate width-table thickness on transverse lines 60, after which 15 designated by the numeral 40 which furnishes the various parts of the toy are assembled and material for the arms of the chair. In the block painted or otherwise decorated. The strip H or 20 shown in Figure 6 the two blanks E and F are the sections cut therefrom may be provided with reversed in position, each having its narrow part suitable openings as indicated by the dotted line 95 36, opposed to the broad base part 38 of the 62 to accommodate pivots 64 or other fastening other end with their intermediate portions oppo- means for the various members. 95

site each other and each consuming substantially one-half of the width of the block. Figure 13 illustrates a modification of the method for the production of a series of two articles 100 25 After the blanks E and F are separated on the which are alike in some respects and different in line 34 they are bored out from above on an other respects, such for instance, as a toy dressing 105 arcuate line 42 as indicated in Figure 7 by the use of a rim guide bit as previously described. The curved line 42 preferably intersects the for- 110 strip is irregular in contour and includes a base 105 30 ward plane of the narrow portion 36 of the blank whereby a concaved front is provided for the back of the chair. By cutting on the line 42 the material is removed to the desired depth 115 from the intermediate central portion 40 of each blank to form the spaced arms 40 of the chair and is irregular in outline, preferably being formed 110 and also to leave the upper plane surface 44 with a plurality of lateral projections 74. 115 of the broad base 38 as the seat of the chair. In this type of chair the base may be left solid 120 as the base of the article representing a heavy 125 type of chair for which the various projections 40 by making further cuts. 125

According to the embodiment here shown each 28, 30 and 32 of the molded strip furnish 130 desirable elements of ornamentation for the completed object. It will be noted that in this particular embodiment of the process the sectional 135 contour of the strip D conforms to the front and rear elevational contour of the completed object. In Figures 9 and 10 there is illustrated a more 140 simple embodiment of the process for producing a representation of a clock or other objects which are plane on two opposite faces. 145

As indicated in Figure 9 there is first formed a molded strip G of the desired sectional contour and then the strip is cut transversely on broken lines such as 46 to produce the blanks 150 for objects such as shown in Figure 10. Each blank when cut on the transverse line or lines 46 is ready for painting and decorating to simulate the desired object such as a clock and in this instance the simulation of the object is 155 carried out entirely by choosing and forming the desired contour and applying surface decorations. 160

The molded strip G may of course be of any 165 desired contour to conform to any contour, whether in plan or elevation, of the object to be produced. In the present instance it is substantially rectangular and is molded to produce 170 any selected plane or curved surfaces with suitable projections or indentations. 175

Figures 9 and 10 are intended merely to represent an example of a simple method of 180 producing a number of like objects such as a toy 185 clock in which the finished article may have a relatively wide base 48, a narrow intermediate portion 50 and a slightly wider top portion 52. 190

In Figures 11 and 12 there is illustrated an 195

It has been previously indicated that my invention is not necessarily limited to the method of producing articles of toy furniture but that 145 it may also be employed for other articles more or less ornamental in character. In Figures 14 and 15 I have illustrated how this method may be employed for producing articles such as book ends. 150

In Figure 14 is shown a molded strip K which may be of any desired contour in cross section, depending upon the desired article.

The strip K is cut into sections of suitable length on transverse lines 82 and then each section is divided into two parts by cutting on an ogee curve or other desired line as indicated by the broken line 84. The last named cut serves to separate the block or section into two complementary members which are in reversed position in the block but which when separated are exact duplicates.

By this embodiment of the invention a plurality of like objects, such as book ends 86, may be produced from a minimum amount of material and with a minimum of labor. These objects may, of course, be suitably decorated as desired.

Figures 16, 17 and 18 illustrate the use of this method in producing other like objects of ornamental character, such as candle sticks, one of the finished articles being illustrated in Figure 18.

A molded strip L is first formed, which in cross section is of I-beam formation, having a web 88 and spaced flanges 90 and 92. The faces of the web portion 88 may be formed on curved lines to produce the desired curved formations in the finished object.

The strip L is cut transversely on irregular lines 94 as indicated in Figure 17, such lines extending through the web portion 88 and the base portions 90 and 92.

Each block or section produced by cutting on the line 94 is then cut on irregular lines as indicated at 96 to separate the block into two parts or blanks from each of which a candle stick or the like may be formed, the two objects being in reversed position in the block as indicated in Figure 17.

When the blocks or sections have been cut as just described, the two objects so produced may receive further treatment for finishing the articles. Each candle stick so formed will have a rectangular base 98 formed from a portion of one of the base flanges 90 and 92 and a standard 100 formed from a portion of the web. It may also have a projection 102 at one side constituting a

handle and said handle portion may be formed from the part which lies opposite the end of the standard portion 100 in cutting the objects from the block. The standard portion 100 may be bored axially at 104 to form a candle receiving socket and the handle portion 102 may be bored transversely at 106 to form a finger grip.

The candle sticks or other articles thus produced may of course be finished and decorated in any desired manner.

It is obvious that a large number of articles such as objects of toy furniture or other toys or similar objects more or less ornamental in character, may be produced by following out the various embodiments of my invention, and it will be understood that the samples here illustrated and described are presented as illustrative of various embodiments of the invention.

By employing this invention in its various embodiments, I am enabled to produce large numbers of like objects, or objects similar in some respects and dissimilar in others, with a minimum of labor and material, thus simplifying the process and reducing the cost of producing such objects.

Some changes may be made in the construction and arrangement of the steps and operations of my method without departing from the real spirit and purpose of my invention, and it is my intention to cover by my claim, any modifications or use of mechanical equivalents, which may be reasonably included within their scope.

I claim as my invention:—

A method of forming a series of articles of toy furniture such as chairs, including the steps of forming an elongated strip of material to suitable contour in cross-section to conform to one external contour of the object to be produced, then severing the strip on transverse right lines to produce a series of blocks, severing each block on a selected irregular line to form blanks for two objects, one reversed relative to the other, and boring out a portion of each blank to remove excess material, and to provide the desired internal contour for a portion of the finished object.
